UNITED STATES PATENT OFFICE

HOWARD D. COOK, OF ELYRIA, AND WILLIAM L. SCOTT, OF LORAIN, OHIO

FURNACE CHARGING APPARATUS

Application filed November 18, 1930. Serial No. 496,530.

This invention relates to apparatus for automatically charging billet heating furnaces and for delivering the heated billets to the rolling mill at predetermined intervals 5 of time.

It is among the objects of this invention to provide simple and automatic control for pusher mechanism which shall be adapted to charge billets at predetermined timed intervals 10 in accordance with the number of pieces it is desired to heat and roll in a given time and which shall be adapted for adjustment to vary the timed intervals to increase or decrease the number of pieces handled in a 15 given period of time.

A further object of the invention is to provide automatic apparatus of the above designated character which shall be adapted for delivering billets to the mill at a uniform 20 and accurate rate and which shall be positive in its operation of charging the billets in accordance with the speed of the operating mechanism.

These and other objects will become more 25 apparent from a consideration of the accompanying drawings in which like reference characters designate like parts and in which Figure 1 is a diagrammatic view of a mechanism for charging billets embodying the 30 principles of this invention and Figure 2 is a wiring diagram of the control mechanism utilized in automatically controlling the operation of the pusher mechanism of Figure 1.

With reference to the drawings, reference 35 numeral 1 designates the billets which are shown mounted in rows and being advanced, step-by-step on a furnace skid pipe 2. The billets are charged by a pusher mechanism comprising a lever 3, the upper end 4 of which is adapted to engage the billets, and having its lower end pivotally connected at 5 to a connecting rod 6 which is operated through a motor operated crank shaft 7.

The operation of the charging mechanism 40 is such that the billets 1, when charged in the path of the pusher 4, are successively advanced a predetermined distance by the pivotal motion of the lever 3 about its pivotal 45 support 8 through the oscillating motion of

the connecting rod effected by the crank shaft 7.

To render the charger operative at predetermined intervals of time, the mechanism shown in Figure 2 is employed and consists 55 of a timing device comprising a disk 9 having a pin 10 for closing contacts 11 and 12 of a connection 13 in an electric circuit. The disk 9 is rotated by a motor 14 through a reduction gear 15 which is adjustable to vary 60 the speed of the disk 9 and consequently the rate at which the contacts 11 and 12 are closed by pin 10. The timer motor 14 is electrically connected to a negative and positive circuit 16 and 17, respectively, the motor being 65 connected or disconnected from the circuit by a main switch 18. The control circuit of the charging motor which is generally designated at 19 is closed by a switch 20 in the connection 13 and the charging motor circuit 70 is opened by the limit switch generally designated at 21. The limit switch comprises a movable arm 22 that is actuated by the crank shaft 7 and switch terminals 23-24 and 23'-24', the terminals 23 and 23' being connected through the conductor 25 to the contacts 11 and 12 and terminals 24 and 24' are connected through a conductor 26 to the negative circuit 16 of the power line. The 75 pusher motor 19 is connected by conductor 27 to the positive circuit 17 of the power line.

When the line switch 20 is in closed position and the timing device closes contacts 11 and 12, the circuit 13 is energized thereby energizing the magnet coils of contactors 28, 80 29 and 30 and also energizing the positive contact 30.

The contactor 28 operates a pair of contacts 31 and 32 which are normally urged in 85 their closed position by a spring (not shown). When the coil of contactor is energized the contacts 31 and 32 are opened and when the contactor 28 is deenergized the contacts 31 and 32 are closed by action of the spring. Since the contacts 11 and 12 are closed only 90 momentarily, the contactors 28, 29, 30 would become deenergized and to prevent this, a circuit connection 33 is provided which, through auxiliary contacts 34 and 35 maintains contactors 28, 29 and 30 in the power 95 100 line.

circuit after contacts 11 and 12 have been broken.

The contacts 34 and 35 of the auxiliary circuit are established through the magnet 5 coil of the contactor 28 becoming energized, and similarly, the magnet coil of the contactor 29 electrically connects auxiliary contacts 36 and 37, which through a relay 38 control the circuit of a contact 39. The magnet coil of contactor 29 closes a pair of contacts 40 and 41, establishing connection with the positive connection of the main power circuit and when contacts 40 and 41 are closing, relay 38 is energized to establish a circuit 10 through the auxiliary contacts 36 and 37 with the magnet coil of the contactor 39. Similarly, contactor 39 controls contacts 42 and 43 which when closed energize a relay 44 that connects the magnet coil of a contactor 45 with the power circuit through contacts 46, 47, and the contactor 45 in turn controls contacts 48 and 49, which when closed, energize the relay 50 that closes contacts 51 and 52 to connect the magnet coil of a contactor 53 with the positive line of the power circuit and the latter closes contacts 54 and 55 to establish a connection of the power circuit with the windings of the armature 56 of the pusher motor 19. The contacts and relays just described operate to disconnect resistances 57, 58 and 59 in the motor circuit.

The operation of the automatic pusher mechanism is briefly as follows: Assuming 35 that the main switch 18 is in its closed position, the timer motor 14 will be energized and operate controls to rotate the disk 9 at a predetermined speed in accordance with the adjustment provided through speed regulation mechanism 15 to close the contacts 11 and 12 at predetermined intervals. When the mill is ready to roll, one of the roll crew closes switch 20 which is conveniently located for that purpose and magnet coils of 40 contactors 28 and 29 are energized thereby opening contacts 31 and 32 and closing contacts 40 and 41. The limit switch is in the position shown in the drawings with the contacts of the movable arm 22 in engagement 45 with the terminals 23 and 24, thereby closing the circuit 25-26. The pusher motor is immediately energized through its connection thus made with the negative and positive circuits of the power line, the connection being 50 through the series shunt field resistance to the main circuit 16 and from the motor armature windings through the circuit 17 connecting with 17', thence through the resistances 57-58-59 and through relay 38, 55 through the closed contacts 40-41, the positive contactor 30 to the main line 17.

When the contactors 39, 45 and 53 become energized through their respective relays, the resistances 57-58-59 are automatically 60 cut out thus bringing the motor up to its

maximum speed. When the pusher arm 3 has advanced its maximum distance the arm 22 of the limit switch is operated through the crank shaft 7 of the pusher mechanism and will break its contacts with the terminals 23-24, opening the circuit 25-26, thereby 70 breaking the circuit of the magnet coil of contactor 28, immediately releasing the contacts 31-32 which short circuits the armature 56 of the pusher motor bringing it to a 75 quick stop.

As the arm 22 of the limit switch moves out of contact with the terminals 23-24, a spring causes the arm 22 to bridge the terminals 23'-24' thus placing the limit switch 80 in position to complete the necessary circuit when the timer disk 9 again closes contacts 11 and 12, whereby the operation of the pusher motor is again repeated.

When the requisite number of billets have 85 been charged to the mill, the switch 20 is open and the control mechanism is rendered inoperative.

When it is desired to vary the time intervals of operation of the timing device, the 90 gear reduction adjustment is made in a well known manner to vary the speed of rotation of the disk 9 to either increase or decrease the speed at which the contacts 11 and 12 are closed thereby obtaining accurate and positive 95 control of the feeding of billets at a uniform and predetermined rate of speed.

By means of the apparatus herein described, it is possible to eliminate an operator at the skelp mill at a substantial saving 100 as well as obtaining precise timing of the movement of billets.

Although one embodiment of the invention has been herein illustrated and described, it will be obvious to those skilled in the art that 105 various modifications may be made in the details of construction without departing from the principles herein set forth.

We claim:

1. An automatic controller for billet charging mechanism comprising a motor for the pusher mechanism, a control circuit for said motor, a timer for periodically closing said circuit, and a limit switch operable by said motor for breaking said circuit. 110

2. An automatic controller for billet charging mechanism comprising a motor for the pusher mechanism, a control circuit for said motor, a timer for periodically closing said circuit, and a limit switch for breaking the 120 circuit, and means for short circuiting the armature of the pusher motor when said limit switch has moved to its open circuit position.

3. An automatic controller for billet charging mechanism comprising a motor for the pusher mechanism, a control circuit for said motor, a timer for periodically closing said circuit, and a limit switch for breaking the circuit, motor starting resistors connected in 125

said circuit, and means for automatically cutting out said resistors to bring the pusher motor up to maximum speed.

4. Apparatus for charging billets at predetermined timed intervals comprising a pusher arm, a motor operating said arm, a control circuit for said motor, a timing mechanism for closing said circuit at predetermined intervals, a limit switch operable by said motor to open said circuit, means for controlling the speed of the pusher motor and means for bringing said motor to a sudden stop when the limit switch is moved to open position.

5. Apparatus for charging billets at predetermined timed intervals comprising a pusher arm, a motor operating said arm, a control circuit for said motor, a timing mechanism for closing said circuit at predetermined intervals, a limit switch operable by said motor to open said circuit, and adjustable means for regulating the timing mechanism to vary the speed of the pusher.

In testimony whereof, we have hereunto set our hands.

HOWARD D. COOK.
WILLIAM L. SCOTT.
